AIR MOVING APPARATUS

Alberto Jorge Morris, Dursley, England, assignor to R. A. Lister & Company Limited, Dursley, England, a British company

Filed Dec. 8, 1965, Ser. No. 512,325
14 Claims. (Cl. 230—116)

ABSTRACT OF THE DISCLOSURE

The air moving apparatus as described comprises an axial flow blower driven by an internal combustion engine. The impeller of the blower is mounted on the engine crankshaft so that the engine and impeller form a unit. This unit is supported within a nacelle by means of struts and stays such that an air flow path past the engine to the impeller is formed, the blades of which terminate close to the nacelle wall. The nacelle wall is supported outwardly by brackets positioned in correspondence to the struts and stays and the internal brackets connected thereto. It is contemplated that the mounting structure may include additional struts or stays which extend axially and outwardly from the engine to the nacelle wall to support axial loads produced in operation and may further include ties between the cylinder heads and the nacelle to oppose any tendency of the unit to oscillate rotationally. The blower also includes straightener vanes at the air outlet of the nacelle.

This invention comprises improvements in or relating to air moving apparatus of the class, hereinafter referred to as the class specified, comprising an axial-flow blower driven by a reciprocating internal combustion engine. Such apparatus is primarily intended for moving massive quantities of air and may be used for a variety of purposes, e.g., air drying of drops and other products or things and ventilation.

According to the present invention, in apparatus of the class specified, the impeller of the blower is carried directly on the engine crank shaft or on a part secured thereto so that the engine and the impeller together form a unit, and this unit is supported coaxially within a cylindrical walled nacelle by a mounting structure of struts and stays which extend from the engine to the cylindrical wall to provide a substantial clearance between the engine and the cylindrical wall forming an air flow path past the engine to the impeller, the blades of which project radially beyond the engine as viewed axially of the impeller and have their tips close to the nacelle wall, the mounting structure where it terminates at the inner surface of the wall being connected to bearers for the apparatus, which bearers are disposed against the external surface of the nacelle wall, in such manner that the wall is relieved of substantial mounting loads.

The apparatus as set forth may be mounted by the bearers on a fixed base to provide a stationary unit, on a wheeled chassis or the like to provide a mobile unit, or on, say, timber baulks to facilitate transportation to a location of use.

In one particular form, the ends of some at least of the struts and stays remote from the engine are pivoted to brackets which fit against the internal surface of the nacelle wall and are rigidly secured to corresponding external brackets, so that the pairs of brackets have the nacelle wall sandwiched between them, the external brackets forming part of the bearer structure and for instance having secured to them braces extending tangentially of the nacelle wall and carrying bearer lugs.

The mounting structure may for instance comprise four pairs of struts or stays, there being two pairs at each

2

end of the engine disposed symmetrically on each side of a vertical central plane. Each pair is pivoted at one end to lugs on the engine and extend substantially at right angles to one another to a corresponding pair of the internal brackets at the nacelle walls, these brackets being interconnected through the associated external brackets and a corresponding one of the tangential braces. This mounting structure may also include struts or stays which extend axially and outwardly from the engine to the nacelle wall to support axial loads produced in operation, and may further include steadies from the cylinder heads of the engine to the nacelle.

One construction of air moving apparatus incorporating the above and other features of the invention will now be described with reference to the accompanying drawings in which:

FIGURES 1 and 2 are a diagrammatic plan and end elevation of the apparatus;

FIGURE 3 is a side elevation in more detail and partly in section;

FIGURE 4 shows details of the engine mounting and bearer structure for the apparatus; and

FIGURE 5 is a section on the line 5—5 of FIGURE 4.

Referring first to FIGURES 1 and 2, the apparatus comprises a unit consisting of a reciprocating internal combustion engine 10 and an impeller 11 of an axial flow blower whereof the hub 11a is mounted directly on a stub extension 10a of the crank shaft of the engine. The impeller 11 has radial blades 11b extending outwardly beyond the engine (as viewed axially of the impeller), there being a small clearance between the tips of the blades and the wall of a cylindrical nacelle 12 within which the unit is centrally supported by a mounting structure.

The impeller or blower may be constructed as described in British patent application No. 40,497/64, the impeller being supported by a bearing directly on the stub extension 10a of the crank shaft and being coupled to it through a centrifugal clutch housing in the hub 11a.

The nacelle 12 as shown has a cylindrical wall 12a (FIGURE 3) strengthened by a number of axially-spaced, external, hollow rectangular hoops 12b. Parts of the wall 12a may be cut away to give access to the engine 10 and the apertures thus provided may be closed by removable covers 13 which may be attached to the hoops 12b.

The air cleaner 15 for the engine is conveniently mounted on the nacelle and connected to the engine inlet manifold by flexible hose 14 and elbow 16.

The exhaust silencer 17 is conveniently mounted on the nacelle wall 12a below the engine 10, there being a flexible connection 18 from the exhaust manifold to the silencer 17 and an exhaust pipe 19 leading from the silencer 17 upwards to an outlet projecting outside the nacelle.

The engine/impeller unit mounting structure comprises a number of struts and stays extending from the crank case 10 of the engine to the nacelle wall 12a. The arrangement is symmetrical about the vertical plane containing the impeller axis and comprises, at each corner of the engine crank case, as viewed in plan, a pair of tubular members 20, 21 FIGURES 1 to 5. The members 20 extend substantially horizontally between, and are pivoted to, lugs 22 on the engine crank case and brackets 23 on the inside of the nacelle wall 12a. The members 21 are likewise pivoted to the lugs 22 and to internal brackets 24. The pivotal connections all include, as shown in FIGURE 5, rubber bushes 25.

The mounting structure also includes tubular stays 26 extending outwardly and axially from lugs 27 on the engine to brackets 28 on the nacelle wall 12a. These stays transmit axial loads from the engine/impeller unit.

At least those loads transmitted by the members 20, 21 are prevented from unduly stressing the nacelle 12 by connecting the members to external support structure for the whole apparatus. The support structure comprises brackets 30a, 30b externally of the nacelle at positions corresponding to the brackets 23, 24 respectively, each external bracket being secured to its corresponding internal bracket by bolts 31. Thus the brackets sandwich the nacelle wall between them. The nacelle wall 12a may nevertheless be strengthened at these points by welded-on plates 36.

The brackets 30a, 30b of an associated pair of the members 20, 21 are interconnected by an angle-section brace 33 which extends substantially tangential to the nacelle wall. The braces 33 each carry a bearer lug 34.

There are thus four such lugs 34 and these enable the apparatus to be bolted to a fixed bed so that the apparatus is stationary, or to a wheeled chassis or the like to make it mobile, or to timber baulks for transportation to a location of use.

The mounting structure for the engine may also include ties 38 (FIGURE 2) between the cylinder heads and the nacelle to oppose the tendency for the engine/impeller unit to oscillate rotationally.

The blower also includes straightener vanes 49 at the air outlet end of the nacelle 12. The vanes 49 are secured at their outer ends to the wall 12a and to a diaphragm 41 at their inner ends.

The diaphragm 41 (FIGURE 3) supports a bearing 42, the inner race of which has a clearance 43 from a prolongation 16b of the stub extension 10a. Normally the bearing 42 provides no support for the engine/impeller unit, but acts in the event of a failure to prevent the blades 11b from contacting the nacelle wall.

I claim:

1. Air moving apparatus comprising:
  - (a) an internal combustion engine,
  - (b) an impeller carried on the engine crankshaft so that the engine and impeller together form a unit,
  - (c) the impeller having blades which project radially beyond the engine as viewed axially of the impeller,
  - (d) a cylindrical nacelle wall surrounding the engine and impeller unit,
  - (e) the tips of the blades being disposed close to the nacelle wall,
  - (f) the engine being spaced from the nacelle wall on all sides to provide an air flow path between the engine and the wall,
  - (g) mounting members extending from the engine to the nacelle wall to support the engine and impeller unit within the nacelle wall,
  - (h) bearing members disposed outside the nacelle wall,
  - (i) the bearing members being separately formed from the nacelle wall and
  - (j) the bearing members engaging the external surface of the nacelle wall at locations where mounting members engage the inner surface of the wall, in such manner that the nacelle wall is relieved of substantial mounting loads.

2. Air moving apparatus according to claim 1 wherein at least one mounting member has a pivotal connecting each end thereof, each pivotal connection including a resilient bush.

3. Air moving apparatus according to claim 1 wherein each mounting member embodies an internal bracket which fits against the internal surface of the nacelle wall, and each said bearing member embodies an external bracket, each internal bracket being rigidly secured to a corresponding external bracket so that the pairs of brackets have the nacelle walls sandwiched between them.

4. Air moving apparatus according to claim 3 and comprising braces secured to the external brackets and extending tangentially to the nacelle wall, and bearer lugs carried by said braces.

5. Air moving apparatus according to claim 4 wherein said mounting members comprise four pairs of struts and stays, there being two pairs at each end of the engine disposed symmetrically on each side of a vertical central plane, lugs on the engine to each of which lugs a pair of struts and stays is pivotally connected at one end, the struts and stays in each pair extending substantially at right angles to one another and each being connected to 20 one of said internal brackets.

6. Air moving apparatus according to claim 1 wherein said mounting members comprise struts and stays extending axially and outwardly from the engine to the nacelle wall to support axial loads produced in operation.

25 7. Air moving apparatus according to claim 1 wherein said mounting members comprise ties from the cylinder heads of the engine to the nacelle wall.

8. Air moving apparatus according to claim 1 comprising a number of axially spaced hoops of hollow rectangular section secured externally to the nacelle wall.

9. Air moving apparatus according to claim 8 comprising apertures in said nacelle wall and removable covers attached to said hoops over said apertures.

10. Air moving apparatus according to claim 1 and comprising an engine exhaust silencer disposed within said air flow path between the bottom of the engine and the nacelle wall.

11. Air moving apparatus according to claim 10 wherein said silencer is of elongated character and is 40 provided with streamlined ends, and is disposed with its major axis in line with the air stream in said air flow path.

12. Air moving apparatus according to claim 10 comprising an engine exhaust manifold disposed in said 45 air flow path near the top of the nacelle, and a fixable pipe extending downwardly from the exhaust manifold to said silencer.

13. Air moving apparatus according to claim 10 comprising an outlet pipe extending upwardly from the silencer and terminating away from the air flow path within the nacelle.

14. Air moving apparatus according to claim 1 and comprising a fixed base on which the air moving apparatus is mounted by the aforesaid bearing members.
